UNITED STATES PATENT OFFICE.

HENRIK V. LOSS, OF PHILADELPHIA, PENNSYLVANIA.

FORGING-MACHINE.

1,094,797.

Specification of Letters Patent. Patented Apr. 28, 1914.

Application filed May 14, 1912. Serial No. 697,151.

To all whom it may concern:

Be it known that I, HENRIK V. Loss, a citizen of the United States, and a resident of the city and county of Philadelphia, 5 State of Pennsylvania, have invented certain new and useful Improvements in Forging-Machines, of which the following is a specification.

My invention relates to improvements in 10 forging machines and the object of my invention is to furnish a machine for forging an axle or other article from a bar or billet.

My invention, although I do not desire to confine it to any particular use, will be 15 described in connection with the forging of axles.

The machine consists of a longitudinally separable substantially stationary central die, two sets of longitudinally separable 20 movable dies and two header dies, each movable system operating hydraulically in any suitable manner. In the drawings the telescopic arrangement is shown and on account of the great size of the machine I prefer this 25 arrangement as it economizes space, it will be understood, however, that any other arrangement of the operating parts serving my purpose may be used.

In the accompanying drawings forming 30 part of this specification and in which similar numerals of reference indicate similar parts throughout the several views: Figure 1, is an end elevation of my forging machine; Fig. 2, a central longitudinal sectional elevation of one side of the machine; Fig. 3, a section of Fig. 6 on line $w-w$; Fig. 4, a section of Fig. 3 on line $u-u$; Fig. 5, a central longitudinal section, upon an enlarged scale, through the dies upon one 40 side of the machine, the central stationary die being transversely split at its middle; Fig. 6, a view similar to Fig. 5, the central die being split longitudinally; Fig. 7, a view similar to Fig. 2, showing arrangement 45 when the central die is split transversely at its middle in addition to being split longitudinally; Fig. 8, a section, upon an enlarged scale, upon the line $y-y$, Fig. 5; Fig. 9, a section of Fig. 7 on line $x-x$; Fig. 50 10, a section of Fig. 7 on line $z-z$; Fig. 11, an enlarged transverse sectional view of the lower part of stationary die, Fig. 10, showing wedge for adjusting it vertically; Fig. 12, a longitudinal sectional view, on an enlarged scale, of one section of central die, Fig. 5, showing means for attaching remov-

able working face thereto; Fig. 13, a section of Fig. 14 on line $s-s$; Fig. 14, an end elevation of the inner end of the movable die blocks showing ends of bolts for operating the fin shearing device after the main upsetting stroke has been completed; Fig. 15, a section of Fig. 4 on line $r-r$; Fig. 16, a detached central longitudinal sectional elevation of the central die, the cutters 38 being omitted for the sake of clearness.

The central die is separable longitudinally into two parts, 1 and 2, and between these parts the body of the article to be forged is formed; in an axle the body would 70 be represented by the part that is substantially included between the wheel seats.

The movable die systems consist each of a longitudinally separable die and a header which need not be split. 3 and 4 are, respectively the two parts of the movable dies and 5 is the header die.

Briefly speaking the several separable dies being separated longitudinally, that is the upper parts being lifted away from the under parts, and the movable die systems being fully moved away from the central die, the bar or billet to be forged is put in place between them and the mechanism which controls the lifting and lowering of the upper 85 die sections is operated to fully close the dies. During this closing movement the movable dies are preferably sunk into the bar or billet at some point, preferably that which is to form the journal of the axle, 90 perhaps the central die also will partly engage the bar or billet but this is not essential. The dies having been closed the movable ones are moved inward until they engage the ends of the central die and the 95 header dies are moved in to complete the forging. These several operations having been performed the dies are opened, the forged article is removed and a new bar or billet is placed in the machine.

Having thus briefly indicated the operation of the machine I will now describe its construction.

The main frame 6, which is supported upon suitable foundations, carries the lower 105 parts of the separable dies and also preferably the plunger or header die. The upper parts of the separable dies are carried by a frame 7 which is guided by and vertically movable upon rods 8 the lower ends of which 110 are carried by frame 6 and the upper ends of which carry immovably a frame 9. The

frame 9 carries fixed pistons 10 which enter cylinders 11 formed in or carried by the movable frame 7. As both ends of the machine are precisely alike I have shown in 5 most of the drawings but one of its ends and from this, I believe, the full construction will be easily understood.

12 are cylinders carried by stationary frame 9. 13 pistons of these cylinders. 14 the piston rods the lower ends of which are secured to movable frame 7. If liquid under pressure be admitted to cylinders 11 it will act against the pistons 10 to lower frame 7 and the dies carried thereby. If 15 liquid under pressure be admitted to cylinders 12 under pistons 13 it will lift these pistons, the connecting rods 14, frame 7 and the parts carried thereby.

20 The means for the admission and exhaust of liquid to the above cylinders are so well known that I do not think it necessary to illustrate them, any of the well known means for this purpose may be used.

I have shown in the drawings two arrangements of the central die. In Figs. 5, 25 7, 12 this die, in addition to being separable longitudinally is separated transversely at its middle the two parts, during the first upsetting operation, being separated and held 30 apart by wedges which are afterward withdrawn to permit the ends of the die to slide toward one another, during the latter part of the stroke of the header die, in order that cutters carried by the ends of the central and 35 movable dies may sever the fin formed between these dies by surplus metal which is squeezed out during the forging at this point.

40 In Figs. 2 and 6 the central die is split longitudinally only.

Referring now to Figs. 1, 3, 4, 5, 7 and 15; 45 15 is a block bolted to the movable frame 7 each side of which is furnished with a lip 16 which are engaged by hooks 18 of a key or wedge 17. 19 is a die block, separate from but carried by the wedge 17 as shown, which carries the upper part or parts 1 of the central die. The lower part 2 of the central die is substantially similarly carried and the 50 several parts for carrying this lower part 2 are numbered similarly with corresponding parts carrying the upper part 1. Fig. 3, is a cross section of Figs. 4 and 5 on the line $w-w$; Fig. 4, a section of Fig. 3 on line $u-u$ and Fig. 15, a section of Fig. 4 on line $r-r$. From these figures it will be seen that the die-blocks surround the die-sections, both the top and bottom die-sections and blocks being similar in construction. The 55 die-sections are secured to their respective die-blocks through the medium of bars 20, which are carried in longitudinal slots in the blocks. The die-sections themselves are furnished with grooves for the bars 20 and 60 these grooves are deeper than the bars so

that they may have a certain amount of vertical play thereon this play being for the purpose of facilitating the stripping of the finished axle from the dies. 21 are shoulders on the grooves in the die-sections to limit the 70 vertical movement of these sections in relation to the die-blocks. The bars 20 may be easily endwise withdrawn from the die-blocks 19 when it may be necessary to remove and replace the die-sections. It is not 75 necessary that the bars 20 extend the whole length of the die blocks, they must be long enough to carry the die-sections and need only extend part way of the length of the die-blocks as shown in Fig. 4. From Fig. 80 15 it will be seen that the inside of the outer circular part of the die-sections, represented in Fig. 3 by the outer circle and in Fig. 4 by $x-y$, is but short and that joining this circular part is the angular part which can 85 move slightly vertically in the angular recesses in the die-blocks, this angular construction being to prevent these parts turning one in relation to the other. 51, Figs. 3, 4 and 15, is a clearance to permit the die-sections to move slightly vertically in the die-blocks for the purpose of moving the die-sections so that the forging may be 90 stripped from them. This stripping movement may be given by the ends of the rods 95 44 after the fin is cut by the cutters or by any other suitable device.

The keys or wedges 17, best shown in Fig. 11, are interposed between the die blocks 19 and the block 15 carried by frame 7 and 100 by setting these wedges in or out the die blocks 19 and the die sections 1-2 carried thereby can be moved up or down for purposes of alinement. As a matter of fact this alinement is only necessary when the dies 105 are changed in the machine. It permits the central die to be alined perfectly with the movable dies and once made usually requires no further attention during the use of the dies.

110 22-23 are, respectively, the upper and lower die blocks for the movable dies. The section 22 is carried by bracket guides 24 bolted to frame 7 as shown in Figs. 5, 9 and 10.

25 are rollers interposed between top of die blocks 22 and frame 7 or a wearing block 26 carried by this frame.

The die block 23 is guided by wearing plate 29 carried by the main frame 6. 28 are 120 rollers interposed between die block 23 and wearing plate 29 carried by frame 6.

The movable dies 22-23 are secured to the front end of a piston 30 which is carried by a cylinder 31.

32 is a pipe through which liquid under pressure is admitted to cylinder 31.

Within the forward end of piston 30 is formed a cylinder 33 which carries a piston 34 the front end of which carries the header 130

die 5. To the rear of the piston 34 is secured a pipe 36 through which liquid is conducted to the cylinder 33 to the rear of piston 34. This pipe moves to and fro with piston 34 5 and is suitably guided as at 37.

In operating the machine, the bar or billet having been placed between the dies, liquid is admitted to cylinders 11 to lower the frame 7 and with it the upper sections 1 and 10 22 of the central and movable dies. When the dies are completely closed the movable ones grip the bar or billet preferably at some little distance from its ends, in the case of an axle at the points to constitute the 15 journal bearings for instance, and liquid is admitted to cylinders 31 to advance the movable dies until their ends engage the ends of the central die 1—2 upsetting the metal of the bar and causing it to completely fill 20 the central die and that part of the movable die which is between its inner end and the part gripped by said movable die. The movable dies having completed their stroke liquid is admitted to cylinder 33 causing 25 piston 34 to advance and the header die to engage and form the extreme outer end or head of the axle, or the movement of this header die is simultaneously with that of the main movable dies.

The bar or billet having been forged the 30 axle is completed by turning the wheel seats and the journal bearings in a lathe and this necessitates that the ends of the axle be centered to engage the centers of the lathe. To 35 form the centers in the axle I furnish the header dies with centers 75 which when the header dies are operated sink into the center of the ends of the axle and form center depressions which require but little additional 40 work to fit them for the lathe. This centering device may or may not be used. The bar or billet is properly proportioned to form the finished article but there will nearly always be a certain amount of surplus metal 45 which will be forced out between adjacent ends of the central and movable dies.

In Figs. 5 and 7 the stationary and movable dies carry cutters 38—39 for severing this surplus metal or fin and in order that 50 these cutters may properly operate, the central dies are divided transversely into two parts 40—41 which are, during the first part of the upsetting operation, held apart by wedges 42—43 carried on the ends of rods 55 44—45. These rods carry pistons 46—47, Fig. 7 which operate in cylinders 48—49. If liquid be admitted to cylinders 49 the rods 44—45 will be moved toward one another and the wedges 42—43 will separate the central die transversely. If it be admitted to cylinders 48 the rods will be separated and the wedges 42—43 moved away from the central die. We will suppose that the movable die blocks 22—23 have been moved in until 60 65 their inner ends have engaged the ends of

the central die blocks 19. During the movement which has resulted in this position the part of the bar included between the points that it is gripped by the movable dies has been upset and a certain amount of metal 70 has been forced between the ends of the dies forming a ring or fin upon the forging. To sever this ring from the forging the wedges 42—43 are moved away from die sections 1—2. This being done the die sections are 75 separated transversely at their middles and if their outer ends be pushed against they will be slid toward one another and over that part of the axle that has been formed in them and the cutters on the movable die-sections 80 will complete the cutting of the fin, now very thin, from the forging.

It now remains to form the head of the axle and this is done by advancing the header dies 5 which are carried by the forward ends of pistons 34, one on each side of the machine, until the inner ends of the header dies have engaged and upset the ends of the bar or billet. When the header die 5 is moved in to engage the end of the bar or 90 billet the outer end of the piston 34 engages the heads of bolts 120, not shown on the general plans on account of the small scale upon which they are made. These bolts are shown in Figs. 13 and 14 and pass longitudinally 95 through the die blocks 22—23 their inner ends being attached to the ends *a—b* of the movable die sections 3—4. When the piston 34 pushes the rods 120 inward these rods push in the ends *a—b* of the die sections 3—4 100 which engage and push together the sections of the central die to sever the fin as before stated.

121 are springs surrounding bolts 120, see Fig. 13, which return these bolts and the 105 ends *a—b* of the movable dies 3—4 to their normal position immediately the pressure of the piston 34 is released.

In Figs. 2 and 6 the central die is divided longitudinally only and in this case the rods 110 44—45 engage the outer sides of the central die sections 1—2 or wearing pieces 80 carried by these sections and are used as strippers to loosen the forged article from the movable dies after the forging is completed. 115 In this case the outer ends of the rods 44—45 form pistons which enter cylinders 49 carried by the stationary frame-work of the machine and are under constant pressure of the liquid in said cylinders hence as soon as 120 the dies are separated by lifting movable frame 7 these rods move the central die a short distance toward each other. The superior pressure exerted upon the frame 7 by the pistons and liquid of its operating means 125 easily overcomes the pressure of the rods 44—45 on the central die sections when the dies are closed preparatory to the upsetting operation.

The adjacent ends of the central and mov- 130

able dies, that is to say the outside ends of the central and the inside ends of the movable dies, are subjected to very heavy duty consequently they wear more or less rapidly, 5 it is therefore desirable that these parts be so made that they can be removed and replaced quickly and economically. For this purpose the ends of the dies are turned out to form hooks or ledges 52, best shown in 10 Fig. 12 to receive pieces 53 which are formed with a groove 66 to engage with hook 52. The pieces 53 carry the actual wearing faces 67 which are secured to them by bolts 68 and nuts 69. The heads 70 of the bolts 68 15 enter and completely fill corresponding holes in the faces of the wearing pieces 67, their shanks at 73 where they rest in the pieces 53 are angular to prevent turning and their inner ends are rounded and threaded to receive nuts 69 which are carried in slots 74 20 formed in the pieces 53. The nuts 69 are furnished with holes 35 to permit them to be turned with a pin or spanner to draw the bolts 68 home and the wearing piece 67 25 tight against the piece 53. This assembling is done previously to hanging the piece 53 upon the hook 52.

The upper movable die section 22 carries 30 a pin 54 which passes into a sleeve 55 carried by or forming part of the lower die section 23 and this pin serves to couple the two die sections together and insures them always retaining the same relative positions whether the dies are closed or open. The 35 sleeve 55 passes up through a slot 56 in the projecting part of the piston 34 which carries the header die, this slot being to permit the movement of the piston past the sleeve. The stuffing box 57 of the piston 34 40 needs to be adjusted from time to time and in order that it may be conveniently reached the longitudinally split cap piece 58 at the end of the piston cylinder 33 which forms a distance piece between the inner ends of 45 the movable dies and the piston cylinder 33 is secured at its outer ends to flanges on the cylinder 33 by bolts 59 and its inner ends are united by a bolt 60 which passes through the slot 56 in the piston 34 as does the sleeve 55. By taking out bolts 59 and 60 the cap piece 58 may be removed so as to permit access to stuffing box 57.

The rollers 28 being beneath the article to 55 be forged are, unless suitably protected, apt to be clogged by scale or dirt falling upon them. To prevent this I attach to the inner end of the die sections 23 an apron 61 the lower end of which carries a weight 62 which always keeps the apron taut. This 60 apron, of a flexible construction, covers rollers 28 when the movable dies are retracted.

Opposite sides of the machine are tied 65 together by bolts 63 which are carried by yokes 64 which carry the cylinders 31 and by bolts 65 passing into the main frame 6.

Having thus described my invention I claim as new and desire to secure by Letters Patent:

1. In an upsetting machine, in combination, a stationary frame enveloping a separate movable frame, said movable frame, means for guiding and means for elevating and depressing said movable frame within said stationary frame, a central separable die one part of which is carried by said stationary frame and the other part by said movable frame, separable longitudinally movable dies one part of which is carried by said stationary and the other part by said movable frame, a header die, a piston carrying said header die, a piston inclosing a cylinder in which said first piston works, a cylinder in which said second piston works, and means for admitting a liquid under pressure to said cylinders. 75 80 85

2. In a forging machine, in combination, a stationary frame enveloping a separate movable frame, said movable frame, guides carried by said movable frame, a die-block carried by said guides and movable longitudinally thereon, an upper die section carried by said die block, rollers interposed between said movable frame and said die-block, a die-block carried by the stationary frame, a die-section carried by and movable 90 longitudinally with said die-block, rollers interposed between said die-block and said frame, and means for actuating said die-blocks and connected parts longitudinally. 95

3. The combination with a die substantially as set forth, of a removable end consisting of an inner and an outer part, means for removably connecting said two parts, and means for removably attaching said parts to the die sections. 100 105

4. In combination, a die section the end of which is turned out to form a hook, a grooved piece adapted to be carried by said hook, a wearing face furnished with longitudinal perforations to receive bolts, bolts 110 passing through said perforations their threaded end entering said grooved piece, and nuts located in said grooved piece for securing said bolts and wearing face.

5. In a forging machine, in combination, 115 a longitudinally separable central die, die blocks carrying said die, and wedges transverse to and back of said die whereby said die sections may be lowered and lifted.

6. In a forging machine, in combination, 120 a longitudinally separable central die, die blocks carrying said die, wedges transverse to back of and carrying said die blocks, and means for carrying said wedges.

7. In a forging machine, in combination, 125 a cylinder, a piston in said cylinder, separable dies actuated longitudinally by said piston, a transversely slotted piston carried in said piston-cylinder, a header die carried by said latter piston, means for admitting 130

liquid under pressure to said cylinders, and a means, passing through the slot in the slotted piston, for separably coupling the separable dies.

5 8. In a forging machine, in combination, a central die split longitudinally and divided transversely, removable wedges for engaging and separating the inner parts of said central die sections, and die blocks 10 10 ingly carrying said die sections.

9. In a forging machine, in combination, a central die split longitudinally and divided transversely into four sections, upper and lower die blocks carrying the upper and 15 lower sections of said die, bars carried by said die blocks, upon which the upper and lower sections of said die are hung and upon which they can slide, and movable wedges passing through said die blocks.

20 10. The combination with the stationary frame, the longitudinally movable die block carried by said frame, the die section carried by and movable with said die block, the rollers interposed between said die block 25 and frame, of a pliable apron adapted to cover the rollers when the dies are retracted.

11. The combination with the stationary frame, the longitudinally movable die block carried by said frame, a die section carried 30 by and movable with said die block and the rollers interposed between said die block and frame, of pliable apron, the upper end of which is attached to the die section and the lower end of which is weighted, adapted 35 to cover the rollers when the die blocks are retracted.

12. In an upsetting machine substantially as set forth, in combination, a piston-cylinder, sliding dies, and a split distance piece 40 or cap carried by said piston-cylinder, adapted to contact with said dies, said distance piece or cap being removably carried by said piston-cylinder as and for the purposes set forth.

45 13. The combination with the central longitudinally separable die of a forging machine, of die-blocks and means for carrying and means for operating the same, die-sections carried by said die-blocks so that they 50 can have a slight vertical movement therein, and means for moving said die sections vertically to facilitate the stripping of the completed forging therefrom.

14. The combination with the central longitudinally split die of a forging machine, of die blocks and means for securing said die sections to said die blocks and for per-

mitting them to have a movement therein toward or away from one another.

15. The combination with the central die 60 of a forging machine, said die being split longitudinally, its outer ends being circular in section and its inner part being rectangular and furnished with shoulders, of a surrounding die block and bars carried longitudinally by said block for carrying said die and permitting a slight vertical movement therein relatively to the die blocks. 65

16. In a forging machine, in combination, a longitudinally split central die, die blocks, 70 means for securing said die sections to said die blocks so that they may have a movement therein in a direction at right angles to their longitudinal axis, and means for moving said die sections toward one another 75 when said die blocks are separated.

17. In a forging machine, in combination, a longitudinally split central die, die blocks, means for so securing said die sections to said die blocks that they may have a movement therein toward or away from one another, and hydraulically operated rods engaging and exerting a constant pressure 80 upon the outer sides of said die sections.

18. In a forging machine, in combination, 85 a longitudinally split central die, die blocks, means for so securing said die sections to said die blocks that they may have a movement therein toward or away from one another, hydraulically operated rods engaging 90 and exerting a constant pressure upon the outer sides of said die sections, and wearing pieces interposed between said rods and die sections.

19. The combination with the movable 95 longitudinally separable dies of a forging machine, of longitudinally separable die blocks the one carrying the upper section and the other the lower section of the die, a sleeve carried by one of said die blocks, 100 and a pin carried by the other die block and entering said sleeve.

20. The combination with the movable longitudinally separable die sections of a forging machine, of longitudinally separable 105 die blocks carrying said die sections, and means carried partly by each of said die blocks for causing said die blocks and dies to close in register.

HENRIK V. LOSS.
